(57) **CLAIM**

We claim the ornamental design for an “electrode power connector,” as shown and described.

DESCRIPTION

FIG. 1 is a top left perspective view of the first embodiment of an electrode power connector showing our new design; FIG. 2 is a top right perspective view thereof;

FIG. 3 is a top plan view thereof;

FIG. 4 is a right elevation view thereof;

FIG. 5 is a left elevation view thereof;

FIG. 6 is a front elevation view thereof;

FIG. 7 is a bottom plan view thereof;

FIG. 8 is a bottom right perspective view thereof;

FIG. 9 is a bottom left perspective view thereof;

FIG. 10 is a back elevation view thereof;

FIG. 11 is a top left perspective view of the second embodiment of an electrode power connector showing our new design;

FIG. 12 is a top right perspective view thereof;

FIG. 13 is a top plan view thereof;

FIG. 14 is a right elevation view thereof;

FIG. 15 is a left elevation view thereof;

FIG. 16 is a front elevation view thereof;

FIG. 17 is a bottom plan view thereof;

FIG. 18 is a bottom right perspective view thereof;

FIG. 19 is a bottom left perspective view thereof; and,

FIG. 20 is a back elevation view thereof.
